United States Patent Office

Des. 212,269
Patented Sept. 17, 1968

212,269

BROILER

William J. Rakocy, Clifton, N.J., assignor to Ronson Corporation, Woodbridge, N.J., a corporation of New Jersey

Filed Oct. 23, 1967, Ser. No. 9,100

Term of patent 14 years

(Cl. D81—10)

Fig. 3.

Fig. 4.

FIG. 5.

FIG. 6.

FIG. 1 is a front perspective view of a broiler showing my new design.

FIG. 2 is a side view thereof.

FIG. 3 is a top view thereof.

FIG. 4 is a bottom view thereof.

FIG. 5 is an end view thereof.

FIG. 6 is an opposite end view thereof.

The rear surface of the broiler shown in FIGURES 1 to 6 is flat and plain.

I claim:

The ornamental design for a broiler, substantially as shown and described.
